Atty.

UNITED STATES PATENT OFFICE.

JOHN P. DOHNEY, OF ENGLEWOOD, ILLINOIS.

WINDOW-VENTILATOR.

SPECIFICATION forming part of Letters Patent No. 350,582, dated October 12, 1886.

Application filed April 27, 1886. Serial No. 200,387. (No model.)

To all whom it may concern:

Be it known that I, JOHN P. DOHNEY, a citizen of the United States of America, residing at Englewood, in the county of Cook and State of Illinois, have invented certain new and useful Improvements in Window-Ventilators, of which the following is a specification, reference being had therein to the accompanying drawings.

10 This invention has for its object to provide a ventilator that either may form the lower bar of the window-sash, or that may be built into the wall below the window-sill to be fixed and permanent, or that may be made portable, 15 and detachable for placing it between the sill and sash of the window, and that can be regulated to either draw foul air from the room or to supply fresh air, or both, as may be desirable; and for that purpose my invention consists of the novel devices and combinations of 20 devices hereinafter described and specifically claimed.

In the accompanying drawings, Figure 1 represents an elevation, Fig. 2 a longitudinal 25 vertical section, and Fig. 3 a transverse vertical section, of the ventilator as arranged with in the lower sash-bar.

Corresponding letters in the several figures of the drawings designate like parts.

30 A denotes the ventilator-casing, which, as shown in Fig. 3, may be part of the lower bar of the window-sash, with the glass plate *a* inserted into a groove in the usual manner. This casing is divided by two partitions, *b*, into 35 three chambers, *C*, *D*, and *D'*, and each such chamber has an opening, *c*, *d*, and *d'*, communicating with the outdoor atmosphere and covered with a wire screening, *e*. The central chamber, *C*, also has an open nozzle, *E*, to its 40 top and exterior of the window-glass, and it has an interior opening that can be closed by a trap-door, *F*, suspended on hinges *f* and provided with turn-latch *g*. This door *F*, when opened, will be sustained on any angular 45 position by a toggle-joint consisting of rigid standard *h*, and of links *i* and *j*, the latter hinged to the upper inward edge of the trap-door, and all the pivotal joints of the several parts tightened enough to provide sufficient 50 friction for holding the door on any desired elevation to which it may be opened; but

this toggle-joint arrangement may be left out, and the hinges *f* may be made to provide sufficient friction for holding the door opened. A diaphragm, *K*, placed on an incline and extending into nozzle *E*, divides the chamber *C* and prevents a direct admission of air through opening *c* into the room. The chambers *D* and *D'* communicate each with the inside of the room through an opening, *m*, that can be 60 closed by a swiveled cover, *n*. A constant circulation of air passing from opening *c* through nozzle *E* outside of the window-glass will create a suction for producing a draft through the opening from under trap-door 65 *F*, when raised, which draft can be regulated by opening such door *F* more or less, and it is provided for exhausting the foul air from the room, while through openings *d* and *m* fresh air is admitted into the room, that can be reg- 70 ulated by covers *m*. The diaphragm *K*, being in contact with the warm air from the room on one side, will warm the air coming in contact with it on the other side, which, thereby becoming lighter, will rise, and thus create 75 circulation, as above stated. A ventilator thus arranged within the window-sash or under the window-sill will not only take up no extra room, but is also always in position for immediate use, is in the proper place most desirable 80 to have it, and will ventilate without causing an unpleasant direct draft of air.

In place of trap-door *F* any other kind of door, gate, or register may be applied for closing or regulating the air-outlet. 85

What I claim is—

1. In a window-ventilator, the chamber *C*, with nozzle *E*, diaphragm *K*, opening *c*, and trap-door *F*, all substantially as described, for the purpose specified. 90

2. In a window-ventilator, the chamber *C*, diaphragm *K*, the wall of said chamber *C* being provided with an opening, *c*, communicating with the exterior atmosphere, and an inward opening closed or regulated by a door 95 or gate, all substantially as and for the purpose set forth.

3. A window-ventilator arranged within the lower sash-bar and consisting of chambers *D*, having an exterior opening, *d*, and a smaller 100 interior opening, *m*, substantially as set forth.

4. A window-ventilator arranged within the

- lower sash-bar and consisting of chambers D, having an exterior screen-covered opening, *d*, and a smaller interior opening, *m*, provided with covers *n*, substantially as set forth.
5. The combination, with the lower sash bar or stile of a window-sash, of a ventilator secured in said lower sash bar or stile, consisting of chamber C, with nozzle E, diaphragm K, opening *e*, and door F, having toggle-joint *h i j*, all constructed and arranged substantially as described, to operate as specified.
- 10 6. A window-ventilator consisting of chamber C, with nozzle E, diaphragm K, opening *e*, and door F, in combination with chambers D, having openings *d* and *m*, the whole being constructed and arranged substantially as set forth. ¹⁵

In testimony whereof I affix my signature in presence of two witnesses.

JOHN P. DOHNEY.
